Sewing-Machine.
No. 225,954
Patented Mar. 30, 1880.

UNITED STATES PATENT OFFICE.

EDDY T. THOMAS, OF NEW YORK, N. Y.

SEWING-MACHINE.

SPECIFICATION forming part of Letters Patent No. 225,954, dated March 30, 1880.

Application filed September 15, 1879.

To all whom it may concern:

Be it known that I, EDDY T. THOMAS, of the city, county, and State of New York, have invented an Improvement in Sewing-Machines, of which the following description, in connection with the accompanying drawings, is a specification.

This invention relates to sewing-machines; and it consists in the combination, with a vibrating shuttle carrying or moving arm, of an oscillating and reciprocating lever, as herein-after set forth and claimed, set in motion by a crank, the said lever, by its peculiar movements, enabling the shuttle-carrier and its shuttle to be moved by a crank in such time with relation to the movement of the needle as is requisite and necessary to sew leather, wherein the shuttle must be in its most forward position as the stitch is completed; or, in other words, it is desirable in this my invention to move the needle and shuttle as in the well-known Howe and other machines employed for leather-stitching.

My invention also consists in the combination, with the main shaft of the machine, its driving-pulley, and a locking device, of a bobbin-winder and connecting devices between it and the said driving-pulley, whereby, by moving the bobbin-winder into operative position to wind a bobbin, the driving-pulley will be loosened upon the said main shaft, all constructed as herein-after set forth and claimed; also, in the combination, with the needle-bar, of a guard or thread-shield, constructed and arranged as herein-after described, to prevent the needle-thread from becoming soiled; also, in the combination, with the needle-bar and stud thereon, of a partially-twisted rod and eye or loop to act as a take-up for the thread, all constructed as herein-after set forth and claimed.

Figure 1 represents a sufficient portion of the under side of a sewing-machine to illustrate my improvements in shuttle-driving mechanism; Fig. 2, a section of Fig. 1 on the line xx ; Fig. 3, a sectional detail of the driving-pulley, showing the locking device, the bobbin-winder, and their connecting devices; Fig. 4, an end view of Fig. 3, the driving-pulley being removed; Fig. 5, a portion of the head of the machine, with a part broken away to show the take-up; Fig. 6, a top view

of Fig. 5; Fig. 7 a cross-section of the twisted shaft of the take-up; Fig. 8, a side elevation of the machine; Fig. 9, a modification of the 55 shuttle-moving parts.

The machine taken as the basis for these my improvements is that known as the "Home" machine, and being well known need not be specifically described, other than to say that 60 the main rotary shaft of the machine extends through the overhanging arm, and by a cam-grooved disk moves the needle-bar, the said main shaft having a bevel-gear, which engages a bevel-gear upon a vertical shaft having at its lower end the crank 5, which actuates the shuttle-driving mechanism.

I have omitted the feed and several other well-known things as not of my invention.

The shuttle-carrying arm b , having its fulcrum at c on a stud attached to the usual cloth-supporting plate or bed d , has at its outer end the steel or other usual shuttle-carrier, e , to engage and move the shuttle f , and attached to said arm at 2 is a slotted arm, g , its slot being at 3. About this same stud vibrates and reciprocates a lever, h , slotted at 4. This lever is connected at its rear end with the crank-pin 5, held preferably on an adjustable block, i , connected with the rotary disk j at the 70 lower end of the usual vertical shaft k , the lower end of which is shown in Fig. 1. This lever h is at its outer end provided with a stud, l , (preferably a roller-stud,) which enters the slot 3 in the arm g , and, as the crank-pin 75 5 travels at regular speed in a circle, the said lever, by its vibrations and reciprocations, causes the stud l to impart to the shuttle-carrier a variable motion, and especially moving it so that it reaches its most forward position 80 and draws upon the shuttle-thread as the needle-thread is drawn taut to complete the stitch, as is customary for leather-stitching. By these devices the time occupied by the shuttle in passing through the loop of needle-thread is but a 85 small fraction of the time of each revolution of the disk j , and for such passage of the shuttle the crank-pin moves only from its full to its dotted line position, Fig. 1, in the direction of the arrow.

The connection between the crank-pin and lever h is kept packed and close by any suitable means.

The usual main rotating shaft p of the ma-

chine has placed loosely upon it a driving-wheel, q , with belt-receiving groove 6, a steel plate or disk, 7, perforated at one or more places to receive the locking device r , being connected with the rear side of the said wheel q .

The locking device (shown as a spring-pressed pin provided with a grooved head, 8) is adapted to slide in a hub, s , fixed upon the shaft p .

The head 8 of the locking device is engaged by a flange or projection, 9, of a loose sleeve, t , connected with the upper end of a lever, u , having an inclined projection, 10, or equivalent, to be acted upon by a slide, w , slotted at 12, guided by a pin, 13, and connected by a link, 14, with the frame of the bobbin-winder x , of any usual construction, it having a pulley, 15, to receive the machine driving-belt.

When a shuttle-bobbin is to be wound the bobbin-winder is turned down, lifting the slide w until it meets the incline 10, when the arm or lever u is, with the sleeve t , moved longitudinally along the main shaft p , and the locking device r is withdrawn from and so as to leave the pulley q loose on the shaft, to be run and not turn the said shaft.

To facilitate the introduction of the needle-thread into the needle-eye, at the top of the needle-bar a^2 a diagonal slot, 17, is cut, and the said slot is intersected at each end by a slot formed at right angles thereto, as at 16.

The needle-thread carried by the needle-bar is very apt to become soiled with oil. To obviate this I have placed about the said needle-bar, above the head a^3 , a guard or shield, b^2 , shown as made of a single piece of wire, connected with the head by a screw, 20.

The take-up is composed of a partially-twisted and flattened rod or bar, h^2 , and an eye-piece, h^x , the ends or journal parts h^3 of the bar resting in bearings made as screws, and therefore adjustable, to compensate for wear. This bar h^2 has its body partially twisted from its center 19 toward each end, as in Fig. 5, leaving a smooth winding-surface at its rear side to be acted upon by the flat-headed stud 41, attached at the front side of the needle-bar a^2 , the said stud always remaining in contact

with the flat side of the said bar, and moving the take-up positively both when giving thread to the needle and when drawing up the thread.

In Fig. 9 I have shown a modification of the shuttle-actuating mechanism. In said figure the rear part of the shuttle-carrier is bored to receive the vibrating and reciprocating part h , therein shown as a round bar.

I claim—

1. The combination of a vibrating shuttle holding and moving arm having a fixed bearing, a lever loosely connected to said arm to move longitudinally with relation to it, and a crank and suitable rotating mechanism to impart an oscillating and reciprocating motion to said lever, substantially as described.

2. The combination of a vibrating shuttle moving arm, an oscillating and reciprocating lever connected to said arm by an extensible joint to drive the shuttle in a curved race, and mechanism to operate the said arm and lever, substantially as specified.

3. The combination of the main shaft, a wheel, g , a plate, 7, having holes therein, a hub, s , and a sliding pin, r , with a flanged sleeve, t , connected with the head of pin r , a lever, u , its incline 10, the slotted slide w , the pin 13, a link, 14, and a bobbin-winder, to operate substantially as specified.

4. The combination, with the needle-bar and head of the machine, of the horizontal guard or thread-shield attached to the upper part of the head of the machine and surrounding the needle-bar below its eye, substantially as described.

5. The twisted take-up bar h^2 , having the eye h^x , in combination with adjustable or compensating bearing-screws h^4 , the adjustable screw 41, the needle-bar, the sewing-machine head, and operating mechanism, substantially as shown.

In testimony whereof I have signed my name to this specification in the presence of two subscribing witnesses.

EDDY TAYLOR THOMAS.
